(57) **CLAIM**

The ornamental design for an exhaust pipe set for a mini van, substantially as shown and described.

DESCRIPTION

FIG. 1 is a partial perspective view of the present design showing an exhaust pipe set for a mini van;

FIG. 2 is a rear view thereof;

FIG. 3 is a side view thereof, the opposite side being a mirror image thereof; and

FIG. 4 is a partial perspective view of another embodiment of the present design showing an exhaust pipe set for a mini van;

FIG. 5 is a rear view thereof;

FIG. 6 is a side view thereof, the opposite side being a mirror image thereof; and,

FIG. 7 is a top view of embodiments corresponding to FIGS. 1 and 4.

The bottom view is disclaimed herein. The broken lines shown herein (portions of the design shown in broken/dashed lines) are for the purpose of illustrating environment and form no part of the claimed design.
